IGNITION TIMING CONTROL

George F. Butkiewicz, Omro, Wis., assignor to
F. Butkiewicz and Sons Company, Omro, Wis.

Application September 30, 1948, Serial No. 51,932

2 Claims. (Cl. 115—18)

1

This invention relates generally to internal combustion motors and more particularly to an outboard motor and still more particularly to means for simultaneously controlling mechanically interconnected throttle control means and ignition timing control means in the type of outboard motor in which a magneto stator plate and the carburetor throttle are connected for simultaneous adjustment.

A primary object of this invention is to provide means whereby an operator can control the directional travel and speed of a boat with one hand, thus allowing greater attention to be given to the matter of navigation of the boat and increasing the safety, as well as the ease, with which motor boats may be operated.

A specific object of this invention is to provide a control handle assembly which can be pivoted upwardly on the outer end of the steering arm, thus providing for greater ease in handling of the assembled motor, as well as for greater ease in crating, shipping and storing the motor.

Another specific object is to provide a control means for an outboard motor, in which the several parts are so integrated with the motor that these parts will not be lost, mislaid or fouled.

Still another specific object is to provide a control means for an outboard motor in which provision is made for reversing the direction of rotation of the actual hand grip control member corresponding to a given change in the speed of operation of the motor, that is, this hand grip may be connected mechanically with the magneto ignition timing control mechanism in two ways so that the same may be rotated either to the left or to the right to cause the same change, this feature being accomplished by providing for the alternative mounting of a drive mitre gear on either side of a mitre gear on a drive shaft connected indirectly with a stator plate.

And a last object to be mentioned specifically is to provide an outboard motor control means which is relatively inexpensive and practicable to manufacture, which is safe and completely convenient to operate, and which will give generally efficient and durable service.

With these objects definitely in view, this invention resides in certain novel features of construction, combination and arrangement of elements and portions as will be hereinafter described in detail in the specification, particularly pointed out in the appended claims, and illustrated in the accompanying drawings which form a material part of this application, and in which:

Figure 1 is a side elevational view of the assembled device on an outboard motor;

Figure 2 is a vertical longitudinal sectional view of a portion of the device, the view being taken substantially on the line 2—2 in Figure 5;

Figure 3 is a vertical transverse sectional view of a portion of what is hereinafter referred to as the housing and contiguous portions;

Figure 4 is a fragmentary sectional view designed to indicate how what is hereinafter referred to as the sector gear is mounted upon the stator plate.

Figure 5 is a fragmentary top plan view of the structure shown in Figure 1;

Figure 6 is a horizontal sectional view, taken substantially upon the line 6—6 in Figure 7; and

Figure 7 is a vertical sectional view, fragmentary in character, taken upon the line 7—7 in Figure 6.

Similar characters of reference designate similar or identical elements and portions throughout the specification and throughout the different views in the drawings.

Referring now to the drawings in detail this invention is adapted to be used with an environment including an outboard motor assembly such as that illustrated in the drawings as having an attaching clamp 12 hinged to a vertical housing 14 which carries a motor generally indicated at 16 and including a crank case 17, fragmentarily illustrated in Figure 7. Such a motor assembly will include a starting pulley 18, a gasoline tank 19, and a stator plate 20 comprising a portion of the ignition timing mechanism. Ordinarily the stator plate 20 will also be mechanically connected, as by a synchronizing cam, with the carburetor throttle, and it will be understood that the device hereinafter described, by adjusting the stator plate, will also adjust the throttle simultaneously and suitably according to well understood principles of motor operation.

40 A spacer member 22, best illustrated in Figures 4 and 7, and a necessary complement of studs or bolts is used to secure a sector gear 24 to the stator plate 20. A sector pinion 26 is in continuous engagement with the sector gear 24 and is supported at the upper end of a housing 28 carried on an attachment plate 30 which is bolted or otherwise secured to the crank case 17 or other suitable portion of the motor assembly, the sector pinion 26 being secured at the upper end of the counter shaft 34 rotatably mounted within the housing 28. The lower end of the shaft 34 carries a mitre gear 36 which is in constant mesh with the drive mitre gear 38. The drive mitre gear is carried on one end of the drive shaft 40 which is journalled in the lower portion 32 of the housing 28. A thrust collar 42 will be

provided, as indicated in Figure 3, and one end of the enlarged portion 32 of the housing will be provided with a screw-in plug member 43, while the other end of the housing portion 32 will be provided with a recess 44 and the drive shaft 40 will be provided with a diametrically disposed bore 46, whereby the drive pinion 38 may be alternatively secured to the drive shaft 40 on either side of the mitre gear 36, thus allowing rotation of the drive shaft 40 in one direction to give alternative directional rotation to the countershaft 34, the arrangement of the drive mitre gear 38 being a matter of preference on the part of the operator of the device.

The drive shaft 40 is provided with a universal joint 48 connecting it with a drive shaft extension 50. The drive shaft extension 50 is journaled within a handle extension 52 which has an offset portion pivoted on the end of the steering handle 54 normally provided in outboard motor assemblies by means of a pivotal connection indicated at 56, to allow movement of the handle extension 52 in one plane relative to the steering handle 54. A preferred embodiment of this invention includes a thimble 58 which is rigidly pinned, as at 60, on the outer end of the drive shaft extension 50, and which is provided with a resilient hand grip 62.

It is preferred that the different parts of this invention shall be enclosed as fully as possible to guard against interference with the person or clothing of the operator and with this in mind, the crank case 11 will be laterally apertured, as indicated at 64 in Figure 6, the housing 28 and contiguous portions being enclosed within the apertured crank case shroud by a crank case patch 66 bolted, as at 68 to cover the aperture 64.

The operation of this invention will be clearly understood upon a consideration of the foregoing description of the mechanical details thereof, taken in connection with the drawings and with the above recitation of the objects of this invention. It will be clear that all of these above objects are amply achieved by this invention.

Obviously variation from the embodiment of this invention set forth in the drawings and specification may be resorted to without departure from the spirit of this invention, the configuration of the hand grip, housing and means of attachment of the device on a motor being dictated in part by the type of motor wherewith this invention is to be used.

Accordingly, this invention should be limited only in accordance with a proper interpretation of the terms used in the subjoined claims.

Having described the invention, what is claimed as new is:

1. In an outboard motor having a casing and mechanically interconnected throttle control means and ignition timing control means, a steering handle on said motor, an ignition timing stator plate, a sector gear on the stator plate, a housing fixed exteriorly on said casing, a sector pinion engaging said sector gear, a countershaft 10 rotatively mounted in said housing carrying said sector pinion at one end of the countershaft, a mitre gear secured to the other end of said countershaft, a drive shaft rotatably mounted on said steering handle of said motor and journaled on said housing and having a drive mitre gear engaging the mitre gear on the countershaft, whereby both throttle and ignition settings may be controlled by manually rotating said drive shaft.
2. In an outboard motor having a casing and mechanically interconnected throttle control means and ignition timing control means, a steering handle on said motor, an ignition timing stator plate, a sector gear on the stator plate, a housing fixed exteriorly on said casing, a sector pinion engaging said sector gear, a countershaft 15 rotatively mounted in said housing carrying said sector pinion at one end of the countershaft, a mitre gear secured to the other end of said countershaft, a drive shaft rotatably mounted on said steering handle of said motor and journaled on said housing and having a drive mitre gear engaging the mitre gear on the countershaft, whereby both throttle and ignition settings may be controlled by manually rotating said drive shaft.
3. In an outboard motor having a casing and mechanically interconnected throttle control means and ignition timing control means, a steering handle on said motor, an ignition timing stator plate, a sector gear on the stator plate, a housing fixed exteriorly on said casing, a sector pinion engaging said sector gear, a countershaft 20 rotatively mounted in said housing carrying said sector pinion at one end of the countershaft, a mitre gear secured to the other end of said countershaft, a drive shaft rotatably mounted on said steering handle of said motor and journaled on said housing and having a drive mitre gear engaging the mitre gear on the countershaft, whereby both throttle and ignition settings may be controlled by manually rotating said drive shaft.
4. In an outboard motor having a casing and mechanically interconnected throttle control means and ignition timing control means, a steering handle on said motor, an ignition timing stator plate, a sector gear on the stator plate, a housing fixed exteriorly on said casing, a sector pinion engaging said sector gear, a countershaft 25 rotatively mounted in said housing carrying said sector pinion at one end of the countershaft, a mitre gear secured to the other end of said countershaft, a drive shaft rotatably mounted on said steering handle of said motor and journaled on said housing and having a drive mitre gear engaging the mitre gear on the countershaft, whereby both throttle and ignition settings may be controlled by manually rotating said drive shaft.
5. In an outboard motor having a casing and mechanically interconnected throttle control means and ignition timing control means, a steering handle on said motor, an ignition timing stator plate, a sector gear on the stator plate, a housing fixed exteriorly on said casing, a sector pinion engaging said sector gear, a countershaft 30 rotatively mounted in said housing carrying said sector pinion at one end of the countershaft, a mitre gear secured to the other end of said countershaft, a drive shaft rotatably mounted on said steering handle of said motor and journaled on said housing and having a drive mitre gear engaging the mitre gear on the countershaft, whereby both throttle and ignition settings may be controlled by manually rotating said drive shaft.
6. In an outboard motor having a casing and mechanically interconnected throttle control means and ignition timing control means, a steering handle on said motor, an ignition timing stator plate, a sector gear on the stator plate, a housing fixed exteriorly on said casing, a sector pinion engaging said sector gear, a countershaft 35 rotatively mounted in said housing carrying said sector pinion at one end of the countershaft, a mitre gear secured to the other end of said countershaft, a drive shaft rotatably mounted on said steering handle of said motor and journaled on said housing and having a drive mitre gear engaging the mitre gear on the countershaft, whereby both throttle and ignition settings may be controlled by manually rotating said drive shaft.
7. In an outboard motor having a casing and mechanically interconnected throttle control means and ignition timing control means, a steering handle on said motor, an ignition timing stator plate, a sector gear on the stator plate, a housing fixed exteriorly on said casing, a sector pinion engaging said sector gear, a countershaft 40 rotatively mounted in said housing carrying said sector pinion at one end of the countershaft, a mitre gear secured to the other end of said countershaft, a drive shaft rotatably mounted on said steering handle of said motor and journaled on said housing and having a drive mitre gear engaging the mitre gear on the countershaft, whereby both throttle and ignition settings may be controlled by manually rotating said drive shaft.

GEORGE F. BUTKIEWICZ.
